CLAIM

The ornamental design for a display stand, as shown and described.

DESCRIPTION

FIG. 1 is a first isometric view of a display stand in accordance with a first embodiment of the invention.

FIG. 2 is a second isometric view of the display stand in accordance with the first embodiment of the invention.

FIG. 3 is a front elevational view of the display stand in accordance with the first embodiment of the invention.

FIG. 4 is a first side elevational view of the display stand in accordance with the first embodiment of the invention.

FIG. 5 is a rear elevational view of the display stand in accordance with the first embodiment of the invention.

FIG. 6 is a second side elevational view of the display stand in accordance with the first embodiment of the invention.

FIG. 7 is a first isometric view of a display stand in accordance with a second embodiment of the invention.

FIG. 8 is a second isometric view of the display stand in accordance with the second embodiment of the invention.

FIG. 9 is a front elevational view of the display stand in accordance with the second embodiment of the invention.

FIG. 10 is a first side elevational view of the display stand in accordance with the second embodiment of the invention.

FIG. 11 is a rear elevational view of the display stand in accordance with the second embodiment of the invention; and,

FIG. 12 is a second side elevational view of the display stand in accordance with the second embodiment of the invention.

The dash-dash broken lines define the bounds of the claimed design and do not form part of the claimed design. The dot-dot broken lines illustrate environment and do not form part of the claimed design.

1 Claim, 8 Drawing Sheets

Related U.S. Application Data

a continuation of application No. 29/631,560, filed on Dec. 29, 2017, now Pat. No. Des. 844,349, which is a continuation of application No. 29/539,706, filed on Sep. 16, 2015, now Pat. No. Des. 806,448.
